US00D651593S

(12) **United States Design Patent**
Hunter et al.

(10) **Patent No.:** US D651,593 S
(45) **Date of Patent:** ** Jan. 3, 2012

(54) **RFID HOLDER**

(75) Inventors: **Scott Hunter**, Arlington, TX (US);
Brian Christopher Witkowski,
Weatherford, TX (US); **Nadiya V. Fuller**, Plano, TX (US)

(73) Assignee: **S.P.M. Flow Control, Inc.**, Fort Worth, TX (US)

(**) Term: **14 Years**

(21) Appl. No.: **29/393,454**

(22) Filed: **Jun. 3, 2011**

(51) **LOC (9) Cl.** 14-03

(52) **U.S. Cl.** **D14/238**

(58) **Field of Classification Search** ..... D14/354, D14/230-238, 299, 358; D6/495; 343/700 R, 343/878-892; 455/90.2, 90.3, 91, 128, 269, 455/344, 347, 562.1, 561; D16/242

(57) **CLAIM**

We claim the ornamental design for the RFID holder, as shown and described.

DESCRIPTION

FIG. 1 is a perspective view of the front, top, and left side of the RFID holder showing an embodiment of the design of our invention;

FIG. 2 is a right side view of the RFID holder of FIG. 1.

FIG. 3 is a top view of the RFID holder of FIG. 1; and, FIG. 4 is a front elevation view of the RFID holder of FIG. 1.

1 Claim, 2 Drawing Sheets
